METHOD OF MAKING DIE-CAST SLIDERS

Noel J. Poux, Meadville, Pa., assignor to Talon,
Inc., a corporation of Pennsylvania

Application November 15, 1945, Serial No. 628,753

5 Claims. (Cl. 18—55)

1

This invention relates to an improved method for making "die-cast" slider blanks.

Such a slider consists generally of a pair of overlying spaced-apart parallel plates or wings connected together at one end by a neck portion with each of the wings having opposed flanges at the sides thereof so as to provide substantially a Y-shaped channel within the slider body through which the fastener elements are adapted to pass. There is usually arranged on the outer side of one of the wings, means such as a lug for attaching a pull or other member thereto for manipulating the slider to open and close the fastener in a manner well-known to those skilled in the art.

Various methods of die-casting sliders have been heretofore suggested and practiced, but such die-casting methods were not entirely satisfactory. Usually, such methods employed complicated cores and multiple-part dies which were not only expensive in their manufacture and to maintain, but an excessive number of flashings were formed on the resulting casting due to the numerous die partings which were objectionable and necessitated expensive equipment and additional operations to remove. Likewise, the use of such dies and cores resulted in uneven and irregular internal slider surfaces, because of the inaccuracies in the movable die parts and/or imperfect fitting thereof. Also, the angles at which the cores or parts could be withdrawn or separated, limited the internal contours obtainable in sliders manufactured by use of such dies and cores.

In the present invention, there is provided a method wherein the slider blank consisting of a pair of wings integrally connected together by a neck portion is die-cast in a single piece in a two-part die and the wings are bent together to overlying position by a simple bending operation to form a finished slider body thereby eliminating the need of cores and other complicated die parts and forming equipment.

Accordingly, it is one of the objects of the present invention to provide an improved method of making die-cast sliders in one piece which is simple and inexpensive, thereby reducing materially the cost of manufacture of sliders.

It is a further object of this invention to provide an improved method of die-casting sliders wherein the slider blanks may, if desired, be cast in a gang die so that a plurality of blanks may be cast at one time interconnected by "gates" which aid in removing the slider blanks from the die and handling in subsequent operations.

Various other objects and advantages of this invention will be more apparent in the course of

2

the following specification, and will be particularly pointed out in the appended claims.

In the accompanying drawings, there is shown for the purpose of illustration, an embodiment which my invention may assume in practice.

In these drawings:

Fig. 1 is a plan view of one part of the die for practicing the method of the present invention.

Fig. 2 is a plan view of the other part of the die.

Fig. 3 is a cross sectional view through the die parts showing the dies separated for removing the slider blank from the die.

Fig. 4 is a sectional view taken on line 4—4 of Fig. 3.

Fig. 5 is a side elevational view of the slider body showing how the wings of the die-cast blank are bent to position to form the finished slider.

Fig. 6 is a plan view of a finished slider body.

Fig. 7 is a sectional view taken on line 7—7 of Fig. 6.

Fig. 8 is a perspective view showing how a plurality of interconnected slider blanks may be cast in a gang die; and

Fig. 9 is a perspective view of the die-cast slider blank of my invention as formed in the die.

Referring more particularly to the drawings, there is shown in Figs. 5 through 6, a slider made in accordance with the present invention, consisting of an integral or die-cast body having an upper plate or wing portion 2 and a lower plate or wing portion 3 integrally connected together at one end by a relatively narrow, substantially wedge-shaped, web or neck portion 4, which divides the wide end of the slider into diverging channels, which channels intersect or join centrally of the slider to provide substantially a Y-shaped channel within the slider body.

Along each of the marginal edges of the wings 2 and 3, there is provided inturned flanges 5 with the opposed flanges being spaced apart so as to provide an opening therebetween which communicates with the Y-shaped channel within the slider.

On the outer side of the upper wing 2 there is provided an outwardly projecting longitudinally extending bar so as to provide a hollow lug portion 6 to which a pull member is adapted to be attached for manipulating the slider to open and close the fastener with which the slider is used, in a manner well-known to those skilled in the art.

In practicing my improved method of manufacturing such sliders, unitary die-cast slider blanks, as shown in Fig. 9 of the drawings, are produced by a die-casting operation. As shown in Figs. 1 through 4 of the drawings, such slider blanks are forming in a die consisting of two

55

parts 8 and 9. The die part 8 has an impression 10 formed in the inner face thereof corresponding to the outer contour of the slider blank, including an impression 12 in which the bar or lug 6 is formed. In the other part 9 of the die, there is formed on the inner face thereof an impression 13 having a contour conforming to the inner surfaces of the slider blank including four impressions 14 for forming the flanges 5 of the slider, a V-shaped impression 15 centrally of the die for forming the wedge-shaped web or neck, and an outwardly projecting portion 16 which cooperates with the impression 12 in the die part 8 to form the hollow lug 6 of the slider blank. These die parts are movable toward and away from each other with each forming one half of the resulting casting 17. The opposed impressions in the die parts for forming the wing portions of the slider are disposed substantially parallel to each other and with the impressions for forming one of the respective wings arranged at an angle substantially of 45 degrees to the vertical, whereby in the resulting casting the wing portions are arranged substantially 90 degrees to each other. On the inner surface of the die part 8 at the parting line of the dies at either side of the wing-forming impressions, there are provided passageways 18 forming the gates for admitting the casting material into the die impressions. There is arranged directly opposite each of these passageways 18 in the lower part of the die, a plurality of pins 19 which extend through holes in this die part and are provided for the purpose of ejecting the casting from the die in a manner hereinafter to be described.

In forming the casting, it will be understood that the two parts of the die are closed with one arranged on top of the other so as to provide an impression between the adjacent surfaces thereof conforming to the slider blank. The die-casting material is forced into the impression between the die parts through the passageways 18 at the parting line of the dies. After the casting has been formed, the dies 8 and 9 are separated, as shown in Figs. 2 and 3, and the pins 19 eject the casting from the impressions of the lower die. It will be noted that when the casting is to be removed that the dies are movable relative to each other substantially in the same plane and in a straight line movement, so that the impressions in the dies are substantially parallel to the wing and neck portions formed by the resulting casting. The resulting casting is a slider blank having the wing portions 2 and 3 thereof arranged angularly (substantially 90 degrees) relative to each other with the wing portions being integrally connected together centrally of the blank by the relatively narrow thickened web or neck portion 4.

It will be understood that many different types of casting or molding material may be employed in practicing my method which is primarily pressure casting; for example, various kinds of metals or metal alloys, as well as thermoplastic materials capable of being molded or cast. In the metal group such base metals as zinc and tin, or alloys containing such metals may be used, or magnesium, aluminum, aluminum alloys, and suitable powdered metals also may be used. In the synthetic plastic or thermoplastic class such materials as cellulose acetates may be employed.

After the casting operation and the casting has been removed from the die, it is trimmed to remove any fins or flashings of metal, as well as the gates 20, so as to provide a slider blank as

shown in Fig. 9. If desired, such blanks may be tumbled in order to smooth and polish the surfaces thereof.

The next step in the method consists in bending the wing portions 2 and 3 toward each other at the neck portion to overlying spaced-apart substantially parallel position to form the finished slider body. In other words, the angularly arranged slider wings 2 and 3 are bent at the neck or web portion 4 to overlying position so that one of the wings and the flanges carried thereby are spaced apart from the other wing and the opposed flanges thereof so as to provide a completely formed slider body. In the bending operation, the slider blank is preferably heated to a temperature of approximately 250 degrees F. and the wings bent as above described while the blank is in such heated condition so as to eliminate any danger of cracking the casting at the neck portion of fissures occurring therein, which might happen if the casting were not heated at the time of bending. While there is shown in Fig. 5 a pair of opposed reciprocating ram-like members 21 for performing the bending operation, it will be understood that any suitable bending mechanism or device may be employed. In performing such bending, there is provided preferably a mouth gage 22 which is positioned between the wings 2 and 3 for insuring that there is provided the proper clearance between the wings after they have been bent to position. In other words, there is provided preferably an anvil or gage 22 positioned between the wings around which the wings are bent, which limits the bending action of the wings toward each other after they contact the anvil so that the wings will not be bent too close together; as it is well-known to those engaged in the manufacture of slide fasteners that it is necessary to have the proper clearance between the wing portions and the flanges in order that the slider can be moved freely along the fastener elements when in use.

It will be seen that my method lends itself to the casting of slider blanks in a gang mold so as to provide a series of interconnected slider blanks, as shown in Fig. 8 of the drawings. Slider blanks generally are rather small and difficult to handle separately and it might be advantageous to cast a series of these blanks in strip form, as shown in this figure, by means of a gang mold as such a strip of slider blanks can be more easily handled in subsequent operations to be formed on the blanks after the casting operation, such as removing the flanges, smoothing, plating and bending.

In the slider blank of the present invention, it will be seen that there is provided a hollow lug portion 6 so as to provide a chamber 23 in the upper wing 2 in under the lug 6, which chamber 23 communicates with the Y-shaped channel of the slider body. By providing such a lug construction, it will be seen that any suitable locking means may be easily assembled within this chamber to provide, for example, an automatic lock slider.

As a result of my invention, it will be seen that there is provided an improved method of making die-cast sliders which is simple and inexpensive and at the same time efficient and effective in its use, thereby providing a method of manufacturing sliders at a minimum cost with a minimum amount of equipment. It will be seen that there are only two major steps involved in forming the slider by my improved method: first, the die-casting of the slider blank in the

simple two-part die; and second, the bending of the slider wings to their spaced apart parallel position to form the finished slider.

While I have shown and described an embodiment which my invention may assume in practice, it will be understood that this embodiment is merely for the purpose of illustration and description, and that other forms may be devised within the scope of my invention as defined in the appended claims.

What I claim as my invention is:

1. The method of making die-cast sliders for slide fasteners of the type having a pair of overlying spaced-apart wings joined at one end by a neck so as to provide an interior Y-shaped channel, which comprises die-casting a pair of slider-forming wings arranged angularly relative to one another, said wing portions being integrally connected together by a thickened substantially diamond-shaped neck portion integrally cast therewith and each of said wing portions having marginal flanges integrally cast therewith on their opposed faces and then bending said wings toward each other at said neck portion to overlying substantially parallel position to form the slider whereby said neck portion is work-hardened as a result of said bending.

2. The method of making sliders for slide fasteners of the type having a pair of overlying wings joined at one end by a neck with each wing having opposed flanges at the sides so as to provide an interior Y-shaped channel, which comprises casting a pair of slider-forming wing portions arranged angularly relative to each other in an impression formed between adjacent surfaces of a pair of dies movable relative to each other substantially in the same plane and in a straight line movement and wherein said surfaces are substantially parallel to the wings and neck portions formed by the resulting casting, said wing portions being integrally connected together by a thickened substantially diamond-shaped neck portion integrally cast therewith and each of said wing portions having marginal flanges integrally cast therewith on their opposed faces separating the dies and removing the casting from therebetween, and then bending the wing portions toward each other at said neck portion to overlying substantially parallel position to form the slider whereby said neck portion is work-hardened as a result of said bending.

3. The method of making sliders of the type having a pair of overlying wings joined at one end by a neck with each wing having opposed flanges at the sides and with one wing having a lug to which a pull member is adapted to be attached, which comprises casting a pair of slider-forming wing portions arranged angularly relative to one another with one of the wings having a lug portion projecting from the outer surface thereof in an impression formed between adjacent surfaces of a pair of dies movable relative to each other substantially in the same plane and in a straight line movement and wherein said surfaces are substantially parallel to the wings, neck and lug portions formed by the resulting casting, separating the dies and removing the casting, said wing portions being integrally connected together by a thickened substantially diamond-shaped neck portion integrally cast therewith and each of said wing portions having marginal flanges integrally cast therewith on their opposed faces from therebetween, and then bending the wing portions toward each other at said neck portion to overlying substantially parallel position to form the slider whereby said neck portion is work-hardened as a result of said bending.

allel position to form the slider whereby said neck portion is work-hardened as a result of said bending.

4. The method of making die-cast sliders for slide fasteners of the type having a pair of overlying spaced-apart wings joined at one end by a neck which comprises die-casting a plurality of blanks simultaneously in a multiple die, each of said blanks consisting of a pair of slider-forming wings arranged angularly relative to one another with each of said wings being integrally connected to the wings of adjacent blanks by means of gates, said wing portions of each of said blanks being integrally connected together by a thickened substantially diamond-shaped neck portion integrally cast therewith and each of said wing portions having marginal flanges integrally cast therewith on their opposed faces, then bending the respective wings of each of said blanks toward each other at said neck portion to overlying substantially parallel position and removing the gates from between wings of said blanks so as to provide a plurality of individual slider blanks whereby said neck portion is work-hardened as a result of said bending.

5. The method of making die-cast sliders for slide fasteners of the type having a pair of overlying spaced-apart wings joined at one end by a neck, which comprises die-casting a plurality of blanks simultaneously in a multiple die, each of said blanks consisting of a pair of slider-forming wings arranged angularly relative to one another with each of said wings being integrally connected to the wings of adjacent blanks by means of gates, said wing portions of each of said blanks being integrally connected together by a thickened substantially diamond-shaped neck portion integrally cast therewith and each of said wing portions having marginal flanges integrally cast therewith on their opposed faces, then bending the respective wings of each of said blanks toward each other at said neck portion to overlying substantially parallel position, removing the gates from between wings of said blanks so as to provide a plurality of individual slider blanks whereby said neck portion is work-hardened as a result of said bending.
